(57) **CLAIM**

I claim the ornamental design for a flotation device, as shown and described.

DESCRIPTION

FIG. 1 is a top perspective view of a flotation device showing our new design in a deflated configuration;

FIG. 2 is a bottom view of the flotation device in a deflated configuration;

FIG. 3 is a top view of the flotation device in a deflated configuration;

FIG. 4 is a side edge view of the flotation device in a deflated configuration;

FIG. 5 is an opposite side edge view of the flotation device in a deflated configuration;

FIG. 6 is an end view of the flotation device in a deflated configuration;

FIG. 7 is an opposite end view of the flotation device in a deflated configuration;

FIG. 8 is a top perspective view of a flotation device of FIG. 1 in an inflated configuration;

FIG. 9 is a bottom view of the flotation device of FIG. 8 in an inflated configuration;

FIG. 10 is a top view of the flotation device of FIG. 8 in an inflated configuration;

FIG. 11 is a side edge view of the flotation device of FIG. 8 in an inflated configuration;

FIG. 12 is an opposite side edge view of the flotation device of FIG. 8 in an inflated configuration;

FIG. 13 is an end view of the flotation device of FIG. 8 in an inflated configuration; and,

FIG. 14 is an opposite end view of the flotation device of FIG. 8 in an inflated configuration.

The broken line showing of the flotation device is for the purpose of illustrating portions of the article that forms no part of the claimed design.
